UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 21,936, dated November 1, 1892.

Application filed October 3, 1892. Serial No. 447,721. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification, reference being had to the accompanying drawing, forming part thereof.

10 The leading feature of my design consists of a continuous scroll of the French renaissance style of drawing running spirally through the center of the design with clusters of leaves and flowers of the rose and other flowers intertwined with the scroll, as represented in the accompanying drawing. Small ornamental scrolls run from the center scroll, filled with flowers, and form part of my design.

The design is printed in any desired color upon tinted paper of any desired color.

What I claim is—

The design for wall-paper herein shown and described.

Witness my hand this 30th day of September, 1892.

CHARLES BOOZE.
